MULTITURN POTENTIOMETER

George J. Mucher, Rochester, N.H., assignor to Clarostat Mfg. Co., Inc., Dover, N.H., a corporation of New York

Filed Sept. 28, 1960, Ser. No. 59,080
10 Claims. (Cl. 338—143)

This invention relates generally to an electrical control device and more particularly to a variable resistance multturn potentiometer whose value is determined by the longitudinal position of a contact arm which is adjusted by rotation of a shaft.

Multturn potentiometers generally consist of a resistance wire wound in the form of a helix and a contact arm which moves along the longitudinal axis of the helix to traverse the various turns thereof in order to alter the value of the resistance. The most common method of moving the contact arm is through use of a rotatable shaft mechanically connected with the contact arm so that rotation of the shaft will effect longitudinal movement of the contact arm. Such an assembly is utilized in equipment wherein high accuracies are sought and the movement of the contact arm must be accomplished in such a manner that little or no electrical error results from the mechanical construction of the device. The rotation of the shaft in assemblies of this type is usually accomplished by a servo motor and because of the accuracies involved it is theoretically desirable to have the extreme of rotation of the servo motor coincident with the extreme movement of the contact arm in both directions. This, of course, is impossible in a practical physical embodiment and one of the main sources of difficulty in the utilization of multturn potentiometers results from the requirement that if the movement of the shaft and the movement of the contact arm are not precisely synchronized, the potentiometer is in serious danger of being damaged. To this end various methods have been used and constructions made to effect a stopping of the contact arm at its extreme position without damaging the assembly even if the shaft is further rotated.

The invention herein disclosed has as its principal object the furnishing of a new multturn potentiometer of such construction that it can resist a high degree of turning torque applied to its shaft without damaging the structure even though the contact arm has reached an extreme position.

Another object of this invention is to provide a multturn potentiometer of rugged construction which suffers very little backlash and which will not alter its electrical characteristics because of dirt forming in the track in which the contact carrier moves.

A further object of this invention is to provide a multturn potentiometer whose movable parts are light in mass, one that requires low torque to move the contact arm, and one that exhibits superior vibration characteristics.

The invention disclosed herein is described in terms of a potentiometer by way of example only and it should be understood that the inventive concept set forth herein can be applied by one reasonably skilled in the art to other variable parameter components whose value is altered by moving a contact arm by rotation of a shaft.

A multturn potentiometer embodying the invention and the manner of using the same is described herein with references to the drawings in which:

FIG. 1 is an exploded top perspective view of a multturn potentiometer constructed in accordance with the teachings of this invention with portions thereof broken away to disclose detailed views of portions thereof;

FIG. 2 is a segmentary view of a portion of the casing and winding of the potentiometer shown in FIG. 1 as

2

viewed in the direction of the arrow designated with the numeral 2;

FIG. 3 is a partially sectional view taken along the line 3—3 in the direction of the arrows as indicated in FIG. 1 showing in cross-section the contact driver, contact carrier, and contact arm utilized in the potentiometer; and

FIG. 4 is a circuit diagram of one possible winding circuit arrangement.

In FIG. 1 a molded cylindrical casing 10 is shown having a resistance wire in the form of a helix 11 embedded in the internal surface thereof. The axis of the helix and the axis of the casing are identical. As seen also in FIG. 2, casing 10 is formed with a helical groove 12 on its internal surface so that each turn of resistance wire 11 is separated from adjacent turns by a portion of helical groove 12 which extends throughout the effective length of casing 10 as does wire 11.

It should be noted that because of the precise manner in which the casing 10, helically formed wire 11, and groove 12 are combined with respect to one another the central axis for each of these elements is identical with the central axis for the remainder of the elements. In other words, the longitudinal axis of the casing 10, grooves 12 and coil 11 is identical.

In its preferred form the casing 10 is molded from a plastic material, however, any suitable non-conducting material can be used for this purpose. In its preferred form, the external surface of casing 10 is formed with longitudinal slots 13 and through openings 14 in order to aid in assembling certain portions of the device and in order to aid in placing external casing 15 over casing 10 when the assembly has been completed.

External casing 15 is shown in FIG. 1 and in the final assembly the casing 10 lies within casing 15 and concentric therewith. Openings 14 are used to aid in the assembly and to allow leads to be brought from within casing 10 to posts 16, 17, 18 and 19 of terminal block 20 which is rigidly fastened to the external surface of casing 15. Openings 21 in casing 10 and 22 in casing 15 are utilized to maintain the two casings rigidly together in the final assembly steps.

One end of casing 15 is closed and a bearing member 23 is embedded in the internal surface thereof and designed to receive corresponding bearing member 23' which is fashioned at one end of shaft 24 which is the axis of the driver member indicated generally by the numeral 25 in the figures. As shown in the figures, the combination of bearing members 23 and 23' form a sleeve bearing supporting one end of shaft 24 which is preferably steel but which could be formed from any suitable material. Although a sleeve bearing assembly is illustrated in the figures, other types of bearings can be utilized.

Circular cover 26 is formed with a portion 27 of external diameter so that it can be received within casing 15 or housing 15 and maintained therein by utilization of openings 21, 22 and 23. The cover 26 is formed also from any suitable material which is a non-conducting material. In the preferred form, control housing 15 and cover 26 are molded from diallyl phthalate. The cover or liner 10 as set forth above is also molded from a non-conducting material. In its preferred form the material of which liner 10 is molded is epoxy resin, however, any suitable material can be used for this purpose.

Bearing member 28 is set in cover 26 to receive corresponding bearing member 28' in order to support the remaining end of shaft 24. Shaft 24 forms the axis for the driver member 25 whose major or body portion 29 is molded from diallyl phthalate to give it an irregular cross-section with radially projecting portions 30, 31 and 32. Body 29 extends longitudinally between bearing members 23' and 28' and the length of body 29 is substantially the same as the length of liner 10.

Body 29 which is originally attached to shaft 24 contains longitudinal slot 33 extending throughout its length. Longitudinal slot 33 is formed to receive metallic U-channel 34 which in turn forms the track for sliding stop 35. Channel 34 is U-shaped in cross-section forming a substantially rectangular track in which sliding stop 35 is maintained against rotational movement but free to move longitudinally.

Light weight disk 36 with a section removed from the central portion thereof corresponding generally to the outline of driver member 25 so that it can receive the same therein, is utilized as a contact carrier. As seen best in FIG. 3 contact carrier 36 is formed to receive the cross-sectional configuration of driver body 29 and to receive radial projecting portion 30 thereof within cut-out section 37 of carrier member 36. Carrier member 36 is disk-like and has a depth substantially equal to the width of helically grooved channel 12 of the liner 10. Carrier member 36 is formed of a light weight material, preferably a plastic, which is non-conducting. An edge thereof at section 36' is received within slot 33' of moving stop 35. The moving stop is preferably metallic and the slot 35 formed therein is preferably of sufficient width that section 36' of the carrier member 36 is maintained therein relatively snugly. Resilient contact arm 38 is fastened at one end 39 by means of bracket 40 and eyelets 41 to contact carrier 36 and electrical lead 42 is electrically in contact with contact member 38.

Contact 38 is designed to engage coil 11 when sector 36' of contact carrier 36 is engaged in slot 35' of moving stop 35 and groove 12 of liner 10. Further, contact 38 is positioned on contact carrier 36 so that the resiliency of arm 38 will yieldingly urge sector 36' within groove 12. In order to accomplish this, the point whereat contact 38 will engage resistance wire 11 is displaced from sector 36' which is to be urged thereby within groove 12.

With such configuration when the driver member 25 is disposed with its ends supported in the appropriate bearings, rotation of shaft 24 will result in the transmission of a rotational force to contact carrier 36 through the radially projecting portion 30 of driver 25. This force will tend to turn contact carrier 36 and move it with groove 12 serving as a track therefor so that contact 38 will traverse wire 11 and such traverse can be accomplished throughout the length of wire 11.

Fixed stops 43 and 44 are provided at either end of channel 34 in the completed assembly. These stops are preferably metallic and have surfaces facing channel 34 so that at either of the extreme positions of contact carrier 36 movable stop member 35 will abut stop 43 or 44 to prevent further movement of the contact carrier 36 longitudinally. Stop 43 is rigidly fastened by any suitable means to the bottom of housing 15 in the general vicinity of bearing 23. Stop 44 is rigidly fastened to cover 26 by any suitable manner in the vicinity of bearing member 28.

Electrically the circuit of the potentiometer shown and described herein is diagrammatically illustrated in FIG. 4. In FIG. 4 the various points of interest are given numbers corresponding to the numbers given the posts on terminal board 20 in FIG. 1. In FIG. 4, however, in order to avoid error, the corresponding numbers are set forth as prime numbers and as tap points on resistance 11' which is a diagrammatic indication of the resistance of wire 11. Physically, post 16 is electrically connected to collector arm 45 shown in FIG. 1 which is designed to engage collector 46 which is electrically connected with arm 38. For this purpose wire 42 is utilized and cutout portion 47 of body 29. Post 17 is connected electrically to one end of wire 11 and post 19 is connected to the remaining end. Post 18 is an optional terminal which can be utilized if desired.

With such a device many advantages result. The device is low in backlash and there is very little relative rotational motion between the various parts. The metal in-

sert or channel 34 carries the contact and also the stop and resists turning at the ends. The light mass contact assembly gives superior vibration characteristics and the disk 36 is slightly loaded in the helical groove and twisted in order to increase the vibration resistant ability of the resultant assembly. The one point drive resulting in the substantially glove fit of radial member 30 within opening 37 provided therefor results in an excellent drive with very little backlash. The placing of the spring contact near the drive point maintains the necessary portion of the disk in the groove in the proper place giving maximum drive force. The helical groove in which the contact carrier 36 travels is displaced from the coil 11 itself and as a result the formation of dust or dirt of any kind within the groove 12 cannot affect the electrical characteristics of the device. Additionally, the concentricity of the major components of the device results in a highly accurate assembly.

Thus, among others, the several objects in the invention as specifically aforementioned, are achieved. Obviously, numerous changes in construction and rearrangement of parts might be resorted to without departing from the spirit of the invention as defined by the claims.

I claim:

1. A multturn potentiometer including in combination a cylindrical hollow casing, a helical groove formed on the inner surface of said casing, a resistance wire consisting of a plurality of continuous turns in the form of a helix disposed in the cylindrical plane of said casing with turns thereof separated by portions of said helical groove, a driver member rotatably supported within said casing with its axis of rotation concentric with the axis of said groove and said wire, a longitudinal slot formed in said driver member, a contact carrier, a portion of said contact carrier having the width of said groove and disposed therein, a second portion of said contact carrier disposed within said slot, means preventing relative rotational movement of said contact carrier and said driver member, a contact arm rigidly supported by said contact carrier and in engagement with one turn of said coil, and conducting means forming an electrical circuit with said contact arm and said coil.

2. A multturn potentiometer in accordance with claim 1 in which the contact carrier is a light weight electrically non-conductive disc section and the contact arm is a resilient electrical conductor rigidly fastened at one end to a surface of the contact carrier so that it engages the coil adjacent the portion of the helical groove in which the contact carrier is disposed.

3. A multturn potentiometer in accordance with claim 1 in which the casing is formed with one surface at each end against which the contact carrier can abut upon reaching the extremity of travel in that direction.

4. A multturn potentiometer in accordance with claim 2 in which the portion of the contact carrier within the helical groove is displaced from the contact arm whereby it is yieldingly urged thereby within said helical groove.

5. A multturn potentiometer in accordance with claim 4 in which the contact carrier is formed with a radial slot and the driver member is formed with a radial projection disposed within said radial slot in substantially a glove fit by which turning moments applied to the driver member can be imparted to the contact carrier.

6. A multturn potentiometer including in combination a cylindrical hollow casing, a helical groove formed on the inner surface of said casing, a resistance wire consisting of a plurality of continuous turns in the form of a helix concentric with said helical groove with turns thereof separated by portions of said helical groove, a driver member rotatably supported within said casing with its axis of rotation concentric with the axis of said groove and said wire, a longitudinal slot formed in said driver member, a light weight electrically non-conducting contact carrier, a sliding stop slidably disposed in said slot, a recess in said sliding stop, a section of said con-

tact carrier having a portion within said recess and a portion in said helical groove, means preventing relative rotational movement of said contact carrier and said driver member, a contact arm rigidly supported by said contact carrier and in engagement with said coil, and conducting means forming an electrical circuit with said contact arm and said coil.

7. A multturn potentiometer in accordance with claim 6 in which the casing is formed with one surface at each end against which the sliding stop can abut upon reaching the extremity of travel in that direction.

8. In a multturn potentiometer a cylindrical hollow casing, a resistance wire consisting of a plurality of continuous turns in the form of a helix concentric with said casing, a helical groove formed in said casing throughout its effective length, a driver member rotatably supported within said casing and said wire with its axis of rotation concentric with the axis of said casing, a contact member mounted on said driver member so that it is longitudinally movable relative thereto and maintained against rotational movement relative thereto and a portion of said contact member disposed within said helical groove whereby rotation of said driver member can cause said contact member to move longitudinally and traverse the turns of said resistance wire, said contact member being formed with an irregular slot therein and said driver member is formed to be received in said slot, and a longitudinal groove is formed in said driver member and said contact member is formed with a section thereof to be movably disposed in said longitudinal groove.

9. In a multturn potentiometer, a cylindrical hollow casing, a resistance wire consisting of a plurality of continuous turns in the form of a helix concentric with said casing, a helical groove formed in said casing throughout its effective length and separating each turn of said

resistance wire from adjacent turns, a driver member rotatably supported with its axis of rotation concentric with the axis of said casing, a contact member mounted on said driver member so that it is longitudinally movable relative thereto and maintained against rotational movement relative thereto, a longitudinal groove formed in said driver member, a section of said contact member movably disposed in said longitudinal groove, and a portion of said contact member disposed within said helical groove whereby rotation of said driver member can cause said contact member to move longitudinally and traverse the turns of said resistance wire.

10. In a multturn potentiometer, a cylindrical hollow casing, a resistance wire consisting of a plurality of continuous turns in the form of a helix concentric with said casing, a helical groove formed in said casing throughout its effective length and separating each turn of said resistance wire from adjacent turns, a driver member rotatably supported with its axis of rotation concentric with the axis of said casing, a contact member, an irregular slot formed in said contact member, said driver member being formed to be received in said irregular slot so that said contact member is longitudinally movable relative thereto and maintained against rotational movement relative thereto and a portion of said contact member disposed within said helical groove whereby rotation of said driver member can cause said contact member to move longitudinally and traverse the turns of said resistance wire.
